UNITED STATES PATENT OFFICE

WILLIAM J. BAUMBERGER, OF DAVENPORT, IOWA, ASSIGNOR TO MICRO MACHINE COMPANY, OF BETTENDORF, IOWA, A CORPORATION OF IOWA

GRINDING MACHINE

Application filed November 5, 1925. Serial No. 67,175.

This invention relates to grinding machines having a plurality of grinding wheels, and more particularly to internal grinders in which grinding wheel spindles are rotated 5 simultaneously about their axes and also in an orbital path about other axes eccentric to the spindles.

With machines in which a single grinding wheel is employed to finish a bore in work 10 which must be ground from opposite directions, and especially when the bore is of two diameters and arranged in axial alignment, either the work must be set up upon the machine for each operation, or the fixture 15 must be adjustable so that opposite ends of the work can be positioned adjacent the wheel. A similar condition is present when a single grinding wheel is employed to finish work which is formed in separate sections to 20 be assembled or related with their finished bores in axial alignment. Considerable time is therefore consumed to accurately position the work, so that the bores to be finished will be presented in the same manner to a 25 tool, and the same is true either when the work is set up for each grinding operation or when the work carrier must be adjusted. Additional time is also required, when a 30 single grinding wheel is used to grind bores of different diameters, as the wheel must be changed between the operations.

An object of my invention is to provide a 35 grinding machine in which there is a pair of grinding wheels intermediate which work can be secured and reciprocated so that bores in two pieces of work, or a bore which is to be ground from opposite directions in an assembled piece of work, can be finished while the work is maintained in a definite fixed 40 position upon a table.

A further object of my invention is to provide a grinding machine in which a reciprocating work table and a pair of grinding wheels can be automatically operated by 45 mechanism in definite relations of movement.

Another object of my invention is to provide a grinding machine in which a reciprocating work table and a pair of grinding wheels can be operated from a single source 50 of motive power, by mechanisms which can

be selectively operated to cause the table to move in a definite speed relation with that of the grinding wheels, or to be moved independently of the speed of the rotation of the grinding wheels.

Still another object of my invention resides in providing mechanism for reciprocating a work table between a pair of grinding wheels which can be operated either by power driven mechanism, or through the 55 same mechanism from adjacent either wheel by manually operated mechanism.

With the above and other objects in view the invention may be said to comprise the machine as illustrated in the accompanying 60 drawings hereinafter described and particularly set forth in the appended claims, or such modifications thereof as will be obvious to those skilled in the art to which the invention appertains. It is, therefore, to be 65 understood that while the following description and accompanying drawings set forth in detail certain means embodying the invention, the disclosed means constitutes but one of the various mechanical forms in which 70 the principle of the invention may be employed.

Reference should be had to the accompanying 75 drawings, forming a part of this specification in which:

Figure 1 is a front elevation of a grinding machine embodying the invention.

Figure 2 is a rear elevation of the machine, the work carrying fixture, grinding wheel spindles and associated parts, and the 80 motor plant not being illustrated as in Figure 1.

Figure 3 is an elevational view, partially in section illustrating the power transmitting plant and the movement of one of the grinder 85 wheels.

Figure 4 is a vertical sectional view taken 90 longitudinally of the machine and illustrating the main drive shaft and the mechanism for reciprocating the work carrying bed.

Figure 5 is a horizontal sectional view of the machine taken on line 5—5 of Figure 4 95 showing a portion of the driving mechanism.

Figure 6 is a vertical sectional view taken 100 transversely of one end of the machine on

line 6—6 of Figure 5 illustrating the driving mechanism.

Figure 7 is a horizontal sectional view of a portion of the machine, taken on line 7—7 of Figure 4, illustrating the mechanism for reciprocating the work carrying bed.

Figure 8 is a vertical section of a portion of the machine taken on line 8—8 of Figure 7, and illustrating the mechanism for controlling and operating the work carrying bed.

Figure 9 is a horizontal sectional view taken on line 9—9 of Figure 1, illustrating one of the hand operated wheels and mechanism operated thereby for reciprocating the work carrying bed.

Referring to the accompanying drawings by characters of reference, the machine consists of a supporting base A which has at the top thereof a bed B upon each end of which spindle carrying heads C are rigidly secured. A fixture, or work holder F is mounted upon the table G which is driven by power, or is movable by hand, to reciprocate intermediate the spindle carrying heads on the bed. The specific structure of the work holder does not concern the present invention, it being sufficient for the present disclosure that this work holder is adapted to be adjusted to rigidly support work, or sections of work, to be ground in alignment with the axes about which the spindles are bodily rotated. The work holder, being mounted on the table G, is moved longitudinally of the machine with the table, by a rack 10 attached to the table which is driven by the pinion 11, as illustrated in Figure 4. The pinion 11 is driven in either direction through the change speed gears in the casing E which in turn are controlled by the gears in the reverse gear box 78 (Fig. 7). The automatic reversal of the table is controlled by adjustable stops in any conventional manner suitable for this type of machine. In addition to a power drive, the table may be operated by either one of a pair of hand wheels 16 as will appear more fully herein-after.

The specific manner of mounting and driving the spindles within the spindle housings 17 is not shown in the drawings, and reference may be had to the pending application for patent Ser. No. 730,626 filed Aug. 7, 1924, as a specific manner of constructing the same, it being understood that both spindles are mounted in a similar manner, are rotated by similar mechanisms, and can be aligned, or offset in parallel relation axially. The spindles within the spindle housings 17 are carried by and project from the heads C, and are rotated simultaneously about their own axis and bodily in an orbital path about their own axis. The spindles within the housings 17 are each provided with a grinding wheel 18, on their projecting end, and the axes of the spindles in this disclosure are arranged in longitudinal alignment. Wherever desired

as for special work the axis of the spindles may be in different parallel planes.

Power transmitting mechanism, which I will now describe, is arranged to rotate the spindles about their axes. A motor 19 (Figs. 1 and 3) may be conveniently located below the machine, and power is delivered therefrom by a belt 20 which extends around the motor pulley wheel 21 and the pulley wheel 22 on the main drive shaft. The main drive shaft extends longitudinally within the machine frame and is formed of a central section 23 (Figs. 1 and 4), intermediate sections 24 which can be connected or disconnected to the central section 23 (Figs. 1 and 4) by intermediate clutches 25, and sections 26 which are connected with the shafts 27 which extend through bearings 28 in the ends of the machine frame and carry pulley wheels 29 on the protruding ends thereof. The sections 26 of the drive shaft are connected with the intermediate sections 24 and the shafts 27 by universal joints 30. Bearings 31 are provided to support the intermediate sections 24 of the drive shaft, and similar bearings 32 are provided to support the central section 23 of the drive shaft. Levers 32, extending externally of the machine frame, are connected by link mechanisms 32A with the clutches 25, so that the operator can selectively connect or disconnect the shafts 24 from the driven central shaft section 23. The grinder spindles within the housings 17 extend beyond the ends of the head casings and a pulley 32 is secured upon each of the projecting ends. A belt 33 extends around the pulleys 29 and 32 at each end of the machine, transmitting power from the main drive shaft to rotate the spindles about their axes.

Pantograph mechanisms 154 (Fig. 1) fully described in the said copending application Serial No. 730,626, connect the bearings 28 (Figs. 1 and 4) mechanically to the outer ends of the grinding wheel spindles in such a way that said spindles may follow their orbital movement freely while maintaining the proper belt tension to transmit power from the pulleys 29 to pulleys 32. The universal joints 30 allow the pulleys 29 to follow the movements of the pantograph mechanisms. Counterweights 151 on levers 152 are associated with pivots 153 and serve to counterbalance the weight of the pantograph mechanisms 154, the levers 152 being attached at their outer ends to projections from the bearings 28.

The mechanism for rotating the spindles in an orbital path about their axes, referred to as being shown in the copending application, is driven from the main drive shaft by the mechanism which I will now describe. A counter shaft 34 (Figs. 2 and 5) is secured exteriorly of the rear side of the machine in bearing brackets 35 and carries a pulley 37. A belt 38 extends around the pulley 37 and a pulley 39 which is secured upon the central

section 23 of the driven shaft. A shaft 40 extends the full length of the machine frame, parallel with the counter shaft 34 and is rotatably mounted in the bearing brackets 41 and 42. A pair of reversely arranged cone pulleys 43 and 44 are arranged intermediate the bearings 36 and 41, the pulleys being the same size and located one above the other with their axes and surfaces parallel and 10 their peripheries slightly spaced. The cone pulley 44 is secured to the shaft 40 and the cone pulley 43 is carried by a shaft 45 which is mounted in the bearing brackets 36. One end of the shaft 45 projects through the bearing 36 and a gear 46 is fixed thereto and arranged to mesh with a gear 47 secured to the counter shaft 34. The cone pulley 43 will be rotated through its connections with the shafts 34 and 45 which are driven from the 15 main drive shaft. A gear 48 is secured to the shaft 40, adjacent the cone pulley secured thereto, and meshes with a gear 49 which is mounted upon the stub shaft 50. This stub shaft 50 is rotatably mounted in the bearing bracket 41 and carries a pulley 51 around which the belt 52 extends. The other end of the shaft 40 is also provided with a gear 53 which meshes with a gear 54, on a stub shaft 55. This shaft carries a pulley around which 20 the belt 56 extends. The belts 52 and 56 extend into the grinder heads to rotate mechanism for causing orbital movement of the grinder spindles simultaneously with the rotation about their axes above referred to. 25 The lower cone pulley, and consequently the shaft 40, is frictionally driven from the upper cone pulley by means of a belt 57 which encircles the lower cone pulley and is adjustable longitudinally of the pulleys to give the 30 desired speed ratio between the two.

For shifting the belt 57 (Fig. 2), there is a yoke 58 straddling the belt and slideable along an inclined guide rod 59 parallel to the contiguous peripheral portions of the conical surfaces of the cones. The yoke 58 is connected to the ends of a cable 60 which runs over a pulley or sheave 61 adjacent one end of the cone pulleys and has its upper and lower runs parallel to the guide rod 59. Adjacent one end of the base, the cable 60 is guided by pulleys 62 and 63 from which they travel over pulleys 64 and 65 carried at one end of a rod 66. The cable extends from the pulleys 64 and 65 around a rotary indicator plate 67, and a guide pulley 68 is provided to maintain the pulley under tension. The indicator 67 is mounted upon a rotatable shaft 69 carrying a drum to which both ends of the cable are secured and by rotating such shaft the yoke 58 will be moved to shift the belt 57 to connect the cone pulleys so that the lower cone pulley will be driven at a desired speed relative to that at which the upper cone pulley is driven. In this manner the speed of

rotation of the tool can be regulated as desired.

As the work is stationary in internal grinding and the spindles revolve in order to carry the wheel around the wall in the work to be ground, this latter movement is actually the work travel, and it is necessary that the rate of speed of the orbital movement of the spindles be variable. In order to remove a maximum amount of stock and to eliminate wheel breakdown or wheel glazing, it is necessary to maintain a correct relation between the wheel surface speed and the work travel. By shifting the belt 57 longitudinally of the cones, the cone 44 will be driven at different speeds from the cone 43 which is driven at a constant speed from the motor, and therefore as the spindles are rotated by the cone 44 a desirable speed of orbital rotation can be obtained.

When the movement of the work is regulated independently of the bodily rotation of the grinders it is difficult to obtain the desired relation of movement, and I therefore provide mechanism whereby the work is reciprocated automatically from the driven cone 44, so that there is a constant ratio between the movement of the work and the orbital rotation of the grinders. The variable speed cone 44 drives the spindles in an orbital path and also drives the work table, thus keeping a proper relation between the table travel and the revolutions per minute of the orbital movement of the spindles. This direct driving relation simplifies the operator's problem. For example, should the table be set to advance .050 inch per revolution of the orbital rotation of the spindles, it will continue to advance .050 inch per revolution of the spindles in an orbital path, even though the rotation of the spindles be increased or diminished in speed. The maintenance of this relation utilizes the full capacity of the grinding wheels without the possibility of overtaxing them.

A pulley 70 is secured to the shaft 40 which is driven from the cone 44, and a belt 71 (Figs. 4 and 5) passes around the pulley 70 and a pulley 72 carried by the countershaft 73 mounted in bearings 74 within the machine frame. A pulley 75 is mounted on the end of the countershaft 73, spaced from the belt 71, and a belt 76 extends around such pulley and a pulley 77 (Figs. 1 and 7) carried on one end of a shaft which projects from the reverse gear box 78 located at the front of the machine.

Power transmitted from the pulley 77 operates the gearing within the box 78 by means of which the pinion 11 is rotated and through its engagement with the rack 10 the work carrying table G is reciprocated. A reversing gear mechanism 79 of the usual bevel gear and intermediate clutch type is located within the box 78, which drives a

stub shaft 80, extending into the casing beneath the bed. The inner end of the stub shaft carries a bevel gear 81 which meshes with a bevel gear 82 on a countershaft 83 which carries a spur pinion 84 meshing with a larger gear 85 on a countershaft 86 (Fig. 8). A series of gears 87 are carried by the shaft 86 and they are of a gradually decreasing size toward the forward end of the shaft. The gears 87 mesh with gears 88 loosely mounted on a parallel shaft 89, the gears 88 varying in size in reverse order as is common in speed changing gearing. The shaft 89 is hollow and slidably therein is a key rod 90 carrying a key 91 which extends through a slot in the shaft 89, and is adapted to engage with any one of the gears 88 to key it to the shaft. Between each of the gears 88 there is a neutral space provided by washers 93 in which the key may be positioned so that the drive of the shaft 89 may be discontinued by shifting the key in either direction out of engagement with any one of the gears 88.

The shaft 89, being thus driven by any one of the pairs of gears 87 and 88, serves to drive the work table G in the following manner. It has fixed thereto at its rear end a pinion 94 which meshes with pinion 95 carried by the horizontal shaft 96 which drives the worm 97 through the coupling 98. The worm gear 99 is carried on a vertical shaft 100 and is driven from the worm 97. The pinion 11 (Fig. 4) being mounted upon the vertical shaft 100 will be rotated in either direction and through its engagement with the rack 10 will reciprocate the table G at a speed which is controlled by the rotation of the cone pulley 44 and the change speed gears which are selectively related.

The rod 90 (Figs. 7, 8 and 9) projects forwardly beyond the end of the hollow shaft 89 and this projecting end has a rack portion 101 formed by closely spaced, parallel, circumferential grooves, the rack portion being engaged by a pinion 102 by means of which the rod carrying the key 91 may be shifted longitudinally. The shaft 104 and sleeve 103 are supported on the frame of the machine by a housing 103'. The pinion 102 is fixed to a sleeve 103 which is loose on the transverse hand wheel shaft 104 and this sleeve has an arm 140 formed integral at the outer end thereof and a handle 141 is provided therewith by means of which it may be turned to shift the key rod 90 to engage any desired gear 88 with the shaft 89 to obtain the desired rate of feed of the table G, or to shift the key rod 90 to a neutral position with key 91 under washers 93 and thus disconnect the power operated mechanism from the shaft 89. The operation that has just been described relates to the means for driving the table G from the motor at desired speed.

I also provide mechanism so that the table

G can be reciprocated by hand from each end of the machine as may be desired, so that the operator can stand adjacent either of the grinding wheels and manually feed the work. In this connection I also provide associated means located and arranged so that the driving connection of the gears 88 with the shaft 89 can be shifted from either end of the machine, into or out of operative engagement.

The shaft 89 is provided at its outer end with a pinion 105 which is in mesh with a gear 106 carried by a countershaft 107 mounted in a bearing bracket 108. A bevel gear 109 is carried by the other end of the countershaft and meshes with the bevel gear 110 secured to the shaft 104. The shaft 96 is also provided with a gear 111 which meshes with pinion 112 secured to a countershaft 113, and a beveled gear 114 is secured to the outer end of such shaft. A shaft 115 similar to 114 and extending parallel with the shaft 104 is loosely mounted in a sleeve 116 which is rotatably carried by the bearing 117 secured adjacent the end of the machine removed from the shaft 104. The hand wheels 16 are secured to one end of each of the shafts 104 and 115 which project from the front wall of the machine frame adjacent each grinder and gears 124, and 110, are carried by the other end of such shafts and mesh with gears 114 and 109, respectively. A collar 118 is loosely mounted on the sleeve 116 and a lever 119 is secured thereto for actuating connecting link 120 which extends across the front of the machine and is pivotally secured at 121 to the collar 118. The other end of the link 120 is pivotally secured at 122 to the collar 123 which is mounted upon the sleeve 103.

The collar 123 (Fig. 9) is loosely mounted upon the sleeve 103, and is provided with an abutment member 142 (Figs. 1 and 9) which is secured therewith and extends from the exterior thereof. The housing 103' is provided with a pair of spaced laterally extending stops 143 between which the abutment member 142 can move a limited degree relative to the sleeve 103. A quadrant 144 is formed integral with the collar 123 and extends adjacent the handle 141 exteriorly of the gear housing, and is provided with a plurality of spaced detents 145 with which the pin 146 carried by the handle 141 can engage to retain the collar and sleeve together. The spring 147 within the handle 141 exerts only a slight pressure which can easily be overcome by the operator. The detents are arranged to receive the pin 146 when the sleeve is rotated into the various positions necessary to cause the key 91 to engage with the several gears 88.

By shifting the key 91 relative to the gears 88, the work table can be driven from the motor at different speeds. The key 91 is carried by the shaft 90, and the rotation of

the gear 102 with the rack 101 will shift the shaft to position the key as desired. The gear 102 is keyed to the sleeve 103 and by rotating the sleeve through the handle 141 the key can be moved. When the key rides 5 on the washers 93 the gears 88 will be in neutral, disconnecting the motor driven mechanism from the table reciprocating gear mechanism.

10 Rotation of the collar 123 is limited by the abutment 142 coming in contact with either one of the stops 143. Sufficient rotation is provided however to permit the sleeve 103 to rotate sufficiently to move the key 91 15 either into or out of engagement with one of the gears 88, depending on the direction of rotation. It is desirable that the key 91 take either an engaged or a disengaged position with no intermediate position, and to this 20 end a pin 148 (Figs. 1 and 9) seated against the spring 149 in the socket 150 is arranged to press on the rounded abutment 142 and direct it against either one of the stops 143. It will be noted that the angular spacing 25 between the detents 145 corresponds to the distance apart of the center lines of the gears 88 on the shaft 89, while the angular space between the stops 143 corresponds to one-half of this distance, and it will be evident 30 that no matter which detent 145 is engaged by the pin 146 the key 91 can be engaged or disengaged by rotating the collar 123 through the angular distance between the stops 143. The collars 123 and 118 being 35 linked together by the rod 120, rotation of either handle 141 or 119 will cause the key 91 to shift its position either into or out of engagement with gears 88. By operating either of the handles 141 or 119, the key 40 can be shifted to connect a pair of gears so that the table will be motor driven, or the gears can be disconnected to permit manual driving of the table. When the gears 88 and the shaft 89 are disconnected, the table 45 can be reciprocated by manually rotating the wheels 16 at either end of the machine. Thus it will be seen that the operator can stand adjacent either grinding wheel and cause the table drive mechanism to move into 50 neutral or driving relation, and can from such position manually operate the driving mechanism, but if it is desired to change the speed of table travel, it is necessary to operate the handle 141, moving it to a different 55 position on the quadrant 144.

With the automatically operated mechanism referred to, I have provided means for changing the ratios of the speeds of the table travel and spindle movements to suit the 60 grinding machine to obtain the best results under various conditions. Such change of the ratio of speed is of course independent of the relationship between the table travel and the bodily movement of the spindle, 65 wherein the latter increases or decreases in

speed when the former increases or decreases in speed. This latter relationship arises from the arrangement whereby the mechanism causing the bodily orbital movement of the spindle and the mechanism for causing longitudinal movement of the table are driven from the same cone pulley, and the rate of rotation of the cone pulley may be varied within relatively small amounts over a relatively wide range by the operator by means of the 70 belt shifting mechanism associated with the cone pulley mechanism as previously explained.

I also provide additional mechanism for transmitting power from the motor to the reverse gear mechanism for operating the table G, in which the drive is directly from the motor and not associated with the spindle drive, as previously described. A pulley 130 is secured upon the countershaft 73, intermediate the pulleys 72 and 75, and a clutch 131 is associated with the pulleys 72 and 130 to disengage both pulleys or to engage either of such pulleys with the shaft 73. The clutch 131 is operated by means of either of two 80 levers 131^a, one adjacent each head, which are connected by a link 131^b to which a shifter lever 131^c is connected. In this manner either one of the pulleys 72 or 130 can be selectively engaged to drive the countershaft 73, or they 85 can be both disengaged. A pulley 132 is secured upon the shaft 34 and a belt 133 extends around the pulleys 132 and 130. When the clutch 131 is operated to cause the pulley 130 to rotate with the shaft 73, the power 90 will be transmitted thereto from the countershaft 34 by the belt 133, which shaft 34 is driven directly from the main drive shaft 23 by the belt 38. The table driving mechanism is operated from the countershaft 73 95 which may be selectively driven directly from the main shaft 23 at a constant fast speed, or from the shaft 40 at a slower variable speed.

By this arrangement it will be seen that 110 the table may be driven relatively rapidly by power from the shaft 23 to bring the work into approximate grinding position quickly. After the work has reached this position, the clutch 131 may be shifted either into 115 neutral, or into rapid or slow table feed. When the clutch 131 engages the pulley 72 with the shaft 73, the pulley 130 is released from the shaft and the table is driven from the cone pulley, and the speed therefore is 120 in a definite ratio with the orbital movement of the grinder spindles which are also driven from the cone pulleys. When the clutch 131 engages the pulley 130, the table is driven rapidly directly from the shaft 34 which receives its power from shaft 23 without driving through the cone pulleys.

In Fig. 2 there is indicated a force feed lubrication system. A rotary pump 160 has its suction side connected by a pipe 161 to 130

a lubricant reservoir 162. A filtering chamber 163 containing suitable filtering screens (not shown) receives overflow oil from various parts of the machine and discharges it into the reservoir 162. To the discharge side of the pump 160 a pipe 164 leads to a header 165 which distributes oil to the various parts of the machine. The pump 160 has a shaft 166 on which a pulley 167 is mounted. A belt 168 transmits power from pulley 169 located on shaft 34 to pulley 167 which operates the pump 160.

With the mechanism described it will be seen that two grinders can be rotated about their axis and also bodily in an orbital path about such axis, that the table can be reciprocated by a direct drive independently of the rotation of the spindles, or in a definite speed relation with the orbital rotation of the spindles. It will also be seen that the table can be disconnected from the power drive and that it can be manually fed from adjacent each grinder through a part of the same mechanism employed where it is driven automatically.

It is to be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. In a grinding machine of the character described, a pair of oppositely disposed grinding wheel spindles, mechanism for rotating said spindles about their axes and orbitally about axes eccentric to said spindles, a work feeding table reciprocable intermediate said spindles, mechanism for reciprocating said table, and common variable speed mechanism for actuating the table reciprocating mechanism and the mechanism for causing orbital movement of the spindles at constant speed ratio.

2. In a grinding machine of the character described, a pair of oppositely disposed grinding wheel spindles, mechanism for rotating said spindles axially, mechanism for rotating said spindles orbitally at variable speeds about axes eccentric to the spindles, a work feeding table reciprocable between said spindles, mechanism including change speed gearing for reciprocating said table, and means for selectively actuating said table reciprocating mechanism from either of said orbital rotating mechanisms and at a definite speed ratio therewith.

3. In a grinding machine of the character described, a pair of oppositely disposed grinding wheel spindles, mechanism for rotating said spindles axially, mechanism for rotating said spindles in orbital paths at variable speeds, a table reciprocable between said spin-

dles, mechanism including change speed gearing for reciprocating said table, common means for driving said table feeding and said orbital rotating mechanisms, and means for selectively connecting or disconnecting said table reciprocating mechanism and both of said spindle rotating mechanisms from said common driving means.

4. In a grinding machine of the character described, a pair of oppositely disposed grinding wheel spindles, separate mechanisms for rotating said spindles axially, and orbitally about axes eccentric to the spindles, a work feeding table reciprocable between said spindles, mechanism for reciprocating said table, means for actuating said orbital spindle rotating mechanisms, means for actuating said axial spindle rotating mechanisms, and means for selectively connecting said table reciprocating mechanism with either of the said orbital actuating means.

5. In a grinding machine of the character described, a pair of oppositely disposed grinding wheel spindles, separate mechanisms for rotating said spindles axially, and orbitally about axes eccentric to said spindles, a work feeding table reciprocable intermediate said spindles, mechanism for reciprocating said table, common actuating means for reciprocating said table mechanism and said mechanism for causing orbital rotation of the spindles, means for disconnecting said table reciprocating mechanism from said common actuating means, and driving means for causing rapid reciprocation of said table when disconnected from said common actuating means, whereby the work may be rapidly adjusted to grinding position, said last named means being independent of the spindle actuation.

6. In a grinding machine of the character described, a pair of oppositely disposed grinding wheel spindles, a work feeding table reciprocable between said spindles, a main drive shaft connected with a source of power, a counter shaft driven from said main drive shaft, a pair of frictionally associated cone pulleys driven from said counter shaft, mechanism operatively connected with one of said pulleys for rotating said spindles in an orbital path, mechanism including reverse and change speed gearing driven from said cone pulleys for reciprocating said table, a second means for driving said table reciprocating mechanism from said counter shaft, and mechanism for selectively connecting or disconnecting either of said means for driving said table reciprocating mechanism.

7. In a grinding machine of the character described, a pair of oppositely disposed grinding wheel spindles, a work feeding table reciprocable intermediate said spindles, power operated mechanism for rotating said spindles about their axes and in orbital paths about axes eccentric to the spindles, means located at each end of the machine for con-

necting and disconnecting the power operated mechanisms for said table, and manually operable means for actuating said table.

8. In a grinding machine of the character described, a pair of oppositely disposed grinding wheel spindles, a work feeding table reciprocable between said spindles, power driven mechanism for rotating said spindles, power driven mechanism including reverse and change speed gearing for reciprocating said table, a pair of manually operative rotatable shafts geared to said reciprocating mechanism for actuating the same when said change speed gears are in neutral, and manually operative means for placing said change speed gears into or out of driving relation, said means being actuatable from adjacent either of said manually operative shafts.

9. In a grinding machine, in combination, a base, a pair of oppositely disposed headstocks mounted on said base, a pair of grinding wheel spindles carried by said headstocks, each said spindle extending toward the opposed headstock and being rotatable about its own axis, and orbitally at variable speeds about an axis eccentric to its own, means for rotating each said spindle about its own axis at a relatively high speed, a reciprocable work supporting table intermediate said headstocks, common driving means for rotating said grinding wheel spindles orbitally and for reciprocating said work supporting table between said headstocks at a definite speed ratio relative to the rate of orbital movement of said spindle, whereby the relative movement between grinding wheels on said spindles and work mounted on said table may be controlled to give advantageous grinding results.

10. In a grinding machine, in combination, a base, a pair of oppositely disposed headstocks mounted on said base, a pair of grinding wheel spindles carried by said headstocks, each said spindle extending toward the opposed headstock and being rotatable about its own axis, and orbitally at variable speeds about an axis eccentric to its own, means for rotating each said spindle about its own axis at a relatively high speed, a reciprocable work supporting table intermediate said headstocks, common driving means for rotating said grinding wheel spindles orbitally and for reciprocating said work supporting table between said headstocks at a definite speed ratio relative to the rate of orbital movement of said spindle whereby the relative movement between the grinding wheels on said spindles and work mounted on said table may be controlled to give advantageous grinding results, and means for varying said definite speed ratio of table reciprocation to spindle orbital speed whereby the most advantageous relative movement between grinding wheel and work may be had for the particular work in hand.

11. In a grinding machine, in combination, a base, a pair of oppositely disposed headstocks mounted on said base, a pair of grinding wheel spindles carried by said headstocks, each said spindle extending toward the opposed headstock and being rotatable about its own axis, and orbitally at variable speeds about an axis eccentric to its own, means for rotating each said spindle about its own axis at a relatively high speed, a reciprocable work supporting table intermediate said headstocks, a common driving means for rotating said grinding wheel spindles orbitally and for reciprocating said work supporting table between said headstocks at a definite speed ratio relative to the rate of orbital movement of said spindle whereby the relative movement between grinding wheels on said spindles and work mounted on said table may be controlled to give advantageous grinding results; and selectively operated means for reciprocating said table independently of said spindle orbital movement and at a relatively high speed whereby positioning of the work relative to the grinding wheel spindles may be quickly accomplished.

12. In a grinding machine, in combination, a base, a pair of oppositely disposed headstocks mounted on said base, a pair of grinding wheel spindles carried by said headstocks, each said spindle extending toward the opposed headstock and being rotatable about its own axis, and orbitally at variable speeds about an axis eccentric to its own, means for rotating each said spindle about its own axis at a relatively high speed, a reciprocable work supporting table intermediate said headstocks, common driving means for rotating said grinding wheel spindles orbitally and for reciprocating said work supporting table between said headstocks at a definite speed ratio relative to the rate of orbital movement of said spindle whereby the relative movement between the grinding wheels on said spindles and work mounted on said table may be controlled to give advantageous grinding results, and means for reciprocating said table manually independently of said spindle orbital movement whereby adjustments of the grinding machine relative to the work and vice versa readily may be made.

13. In a grinding machine, in combination, a base, a pair of oppositely disposed headstocks mounted on said base, a pair of grinding wheel spindles carried by said headstocks, each said spindle extending toward the opposed headstock and being rotatable about its own axis, and orbitally at variable speeds about an axis eccentric to its own, means for rotating each said spindle about its own axis at a relatively high speed, a reciprocable work supporting table intermediate said headstocks, common driving means for rotating said grinding wheel spindles orbitally and for reciprocating said work supporting table

between said headstocks at a definite speed ratio relative to the rate of orbital movement of said spindle whereby the relative movement between the grinding wheels on said spindles and work mounted on said table may be controlled to give advantageous grinding results, selectively operated means for reciprocating said table independently of said spindle orbital movement and at a relatively high speed, and means for reciprocating said table manually independently of said spindle orbital movement whereby adjustments of the grinding machine relative to the work and vice versa readily may be made.

14. In a grinding machine, in combination, a base, a pair of spaced oppositely disposed headstocks mounted on said base, a pair of grinding wheel spindles carried by said headstocks, each said spindle extending toward the opposed headstock and being rotatable about its own axis, and orbitally about an axis eccentric to its own, means for selectively or simultaneously rotating each said spindle about its own axis at a relatively high speed, a reciprocable work supporting table intermediate said headstocks, common driving means for rotating said grinding wheel spindles orbitally at variable rates of speed and for reciprocating said work supporting table intermediate said headstocks always at a definite speed ratio relative to the rate of orbital movement of said spindle, whereby the reciprocative speed of said table may be maintained at a definite ratio to the orbital speed of said spindles regardless of the particular orbital speed of said spindles, means for varying said definite speed ratio of table reciprocation relative to spindle orbital speed, selectively operated means for reciprocating said table at a speed independent of said spindle orbital speed, and means for reciprocating said table manually, whereby adjustments of the grinding machine relative to the work, and vice versa, readily may be made.

45 In testimony whereof I affix my signature.
WILLIAM J. BAUMBERGER.

CERTIFICATE OF CORRECTION.

Patent No. 1,730,838.

Granted October 8, 1929, to

WILLIAM J. BAUMBERGER.

It is hereby certified that error appears in the printed specification of the above numbered patent requiring correction as follows: Page 2, line 92, for the figure "32" read "32'"; page 6, lines 94 and 95, claim 5, strike out the word "reciprocating" and insert the same to follow after the word "table" in line 95, same claim; and that the said Letters Patent should be read with these corrections therein that the same may conform to the record of the case in the Patent Office.

Signed and sealed this 12th day of November, A. D. 1929.

(Seal)

M. J. Moore,
Acting Commissioner of Patents.
